UNITED STATES PATENT OFFICE.

ALEXANDER McMILLAN, OF PRINCETON, NEW JERSEY.

FLYING TARGET.

1,368,176.

Specification of Letters Patent.

Patented Feb. 8, 1921.

Application filed July 6, 1920. Serial No. 394,146.

To all whom it may concern:

Be it known that I, ALEXANDER McMILLAN, a citizen of the United States, and a resident of Princeton, in the county of 5 Mercer and State of New Jersey, have invented a new and Improved Flying Target, of which the following is a full, clear, and exact description.

This invention relates to flying targets, 10 and has particular reference to one which is indestructible.

An object of the invention is to provide a flying target which can be used over and over again without its utility being impaired 15 by constant use.

Another object resides in the provision of means whereby the target when struck by shot will be separated into several parts and thereby fall, indicating a hit, and at the 20 same time so constructed as to be readily reassembled without damage.

Other objects reside in the particular construction and arrangement of parts as clearly set forth in the following description and 25 claims taken in connection with the accompanying drawing.

The invention comprises in general a flying target having a plurality of wing portions with turnedup outer edges, so that 30 when the target is revolved the turnedup propeller edges tend to cause the target to support itself in the air so that it more truly flies than most clay targets which are merely thrown through the air. The various portions 35 of the target are similar in shape and are detachably connected together by means of a temporary resilient gripping engagement between certain of the parts of each portion with similar parts of another portion, whereby the target can be readily assembled and when hit by a shot instantly falls apart.

The fact that the target falls apart into its several separate portions when hit by 45 shot makes it very easy to register hits in shooting contests, and the fact that these parts when separated are not destroyed but can be readily assembled in their normal condition and relation makes the target economical in use, as it can be used many times over.

This target may be used with any suitable machine, if desired, and is adapted to be used with a machine as shown and described 55 in my Patent No. 1,332,735 entitled Shooting trap, issued March 2, 1920.

The invention is illustrated in the accompanying drawing, of which—

Figure 1 is a plan view of the device;

Fig. 2 is a vertical section taken on the 60 line 2—2 of Fig. 1;

Fig. 3 is a perspective view of the parts of the target shown in Figs. 1 and 2 in separated condition;

Fig. 4 is a plan view of a modified form 65 of target having only two propeller surfaces;

Fig. 5 is a sectional view of the same taken on the line 5—5 of Fig. 4; and

Fig. 6 is a perspective view of the wing 70 elements of the target shown in Figs. 4 and 5, shown in their separated condition.

The invention as shown in the drawing comprises a flying target which in one form is made of two wing portions, each portion 75 having two propeller surfaces connected by an intermediate body portion. The propeller surfaces are indicated by the numerals 1, 2, 3 and 4; and the body portion, by the numerals 5 and 6. Each body portion is 80 provided with central square apertures 7 through which, if desired, the shaft of an impelling or throwing machine may be inserted.

On one of the body portions, such as 5, 85 ear portions 8 and 9 are struck up out of the metal of the body portion and sloped upwardly and slightly inclined toward each other, as shown in Fig. 3. The portions 8 and 9 are struck up on opposite sides of the 90 aperture 7 in line with the longitudinal axis of the body portion 5. The body portion 6, which is provided with a similar aperture 7, is provided with struck-up ear portions 10 and 11 shaped similarly to portions 8 and 9 95 but which are struck up on opposite sides of aperture 7 of body portion 6 in a line parallel to the transverse axis of body portion 6. The ear portions 8, 9, 10 and 11 are formed integral with the metal of the wing 100 portions and are resilient. As shown in Figs. 1 and 2, the two wing portions are assembled by inserting the ear portions 10 and 11 through the apertures 12 and 13 in the body portion 5 so that their upwardly 105 curved resilient inner surfaces lie along the outer similarly curved surfaces of the ear portions 8 and 9, thereby achieving a resilient gripping engagement between the ear portions whereby the body portions are 110 maintained in their proper relation.

As shown in Figs. 4, 5 and 6, a flying

target is provided having only two propeller surfaces 14 and 15, each provided with body portions 16 and 17 and apertures 18 similar to the above-mentioned aperture 7. 5 The body portions 16 and 17 are resiliently held together by means broadly similar to the engaging means above mentioned. This particular modification comprises a slot 19 in the body portion 17 on one side of the aperture 18, and a resilient fastener stud 20 on the other side of the aperture 18. The body portion 16 is provided with an end portion 21 adapted to be inserted in the slot 19, and with an aperture 22 into which the resilient fastener stud 20 can be inserted. As shown in Figs. 4 and 5, by slipping the end portion 21 into the slot 19 from the under side of body portion 17, and then pressing the resilient fastener stud 20 into the aperture 22, the two body portions 16 and 17 are resiliently gripped together.

In both these forms of flying targets, it will be readily perceived that it will require 25 only a slight blow on either of the body portions or the propeller surfaces to separate the two body portions, since the gripping engagement between the body portions is only heavy enough to keep them assembled until struck by shot.

What I claim is:

1. A flying target comprising a plurality of propeller portions and resilient connections therebetween whereby the impact of shot thereon will separate the propeller portions from one another.

2. A flying target comprising a plurality of propeller portions and resilient members on each propeller portion, adapted to engage 40 each other when the portions are assembled, the engagement of the portions being only sufficient to normally hold them assembled, whereby the impact of shot thereon will separate the wing portions from one another.

3. A flying target comprising a plurality of propeller portions, integral resilient members on each propeller portion adapted to engage each other when the portions are 45 assembled, the engagement of the portions being only sufficient to normally hold them

assembled, whereby the impact of shot thereon will separate the wing portions from one another.

4. A flying target comprising a plurality 55 of wing portions of resilient material, each portion having integral struck-up ear portions, the ear portions of one wing portion adapted to lie along and resiliently engage the ear portions of another wing portion 60 when the wing portions are assembled to hold the wing portions lightly together whereby the impact of shot thereon will separate the wing portions from one another.

5. A flying target having a wing portion, said wing portion comprising a propeller surface at one end, a body portion having an aperture centrally located therein, and a resilient integral struck-up ear portion 70 on one side of said aperture.

6. A flying target having a wing portion, said wing portion comprising a propeller surface at one end thereof and a body portion having an aperture, engaging means 75 on the body portion on one side of said aperture and adapted to engage with the body portion of another wing portion.

7. A flying target having a pair of wing portions, each of said wing portions comprising a propeller surface at one end thereof and a body portion having an aperture therein, engaging means disposed on opposite sides of the aperture of one of said body portions in line with the longitudinal 85 axis thereof, and engaging means disposed on opposite sides of the aperture of the other of said body portions in line with the transverse axis thereof, said engaging means adapted to lightly and resiliently contact 90 with each other when the two wing portions are assembled whereby the impact of shot thereon will separate the wing portions from one another.

8. A flying target comprising a plurality 95 of propeller portions, said portions being separable and held in their assembled relation only by the resilient contacting engagement of integral members on each of said propeller portions.

ALEXANDER McMILLAN.
